UNITED STATES PATENT OFFICE.

HERMAN HENRY LIEBENBERG, OF PLATTEVILLE, WISCONSIN.

ADJUSTABLE REVOLVING HOLDER FOR GAME-BOARDS, &c.

SPECIFICATION forming part of Letters Patent No. 674,782, dated May 21, 1901.

Application filed April 10, 1900. Serial No. 12,357. (No model.)

To all whom it may concern:

Be it known that I, HERMAN HENRY LIEBENBERG, a citizen of the United States, residing at Platteville, in the county of Grant and State of Wisconsin, have invented a new and useful Adjustable Revolving Holder, of which the following is a specification.

My invention relates to improvements in adjustable revolving holders for game-boards, and pertains to a device which is particularly adapted for holding and revolving game-boards, such as crokinole or bombards, also painting and drafting boards, or objects of a like nature.

15 In the accompanying drawings, Figure 1 is a central vertical sectional view of my invention. Fig. 2 is a top plan view. Fig. 3 is a bottom plan view. Fig. 4 is a detailed sectional view of one of the revolving arms. Fig. 20 5 is a detailed sectional view of one of the stationary arms, showing the adjustable cleat. Fig. 6 is a transverse sectional view of the arm B.

Referring now to the drawings, A indicates 25 the top of an ordinary table; B, two stationary arms resting thereon. The stationary arms B intersect at right angles and are mortised, so as to bring their lower and upper surfaces in the same plane. Braces n, extending between the arms B, serve to hold the arms in 30 a rigid position. The lower surface of the arms B and braces n may be covered with felt or like material to prevent scratching or scarring the table. The revolving portion D may 35 be made of a single plate, with longitudinal grooves for the reception of adjustable cleats, as will be explained hereinafter; but I prefer to carry out my invention in the following manner:

40 D indicates the revolving arms, which are arranged at right angles and mortised at the point of intersection, thus bringing the upper and lower surfaces of each arm in the same plane. At the point of intersection of the 45 respective arms B and D, I provide a vertical circular recess adapted to receive a pivotal pin H, about which the arms D revolve. On the end of the arms D, I provide cleats X, the 50 said cleats having a longitudinal recess g and are laterally adjustable by means of a set-

screw f, thus enabling the operator to adjust the arms to receive and revolve various-sized boards. The cleats X are provided with notches or rabbets for receiving the depending flange M of a crokinole or other board K. 55 The rabbet R will also serve this purpose. The cleats X having a shoulder adapted to receive the depending flange of a game-board and being laterally adjustable, it will be seen that the game-board can be readily fastened 60 or locked and prevented from slipping while it is revolved.

At each end of the stationary arms B, I provide a depending laterally-adjustable cleat or bearing-block C for the purpose of adjusting the holder to various-sized tables. The adjustment of the block C is accomplished by providing a recess or groove e in the end of arms B for receiving the screw d, which is operated by the thumb-screw c, as illustrated 70 in Fig. 5.

From the above description it will be seen that I provide a light yet durable revolving holder for game-boards or similar objects, which can be readily adjusted and securely 75 attached to various-sized tables in a manner which will prevent the movement of the arms B, thus preventing them from scratching or scarring the table.

Through the medium of the cleats X on the 80 revolving arms D it will be seen that the game-boards or like objects of different sizes can be securely held in position without necessarily resting the center of the board on the arms D, thus protecting the lower surface of 85 the board.

Having thus described my invention, what I claim, and desire to secure by Letters Patent, is—

1. In a revolving game-board holder comprising the lower stationary portion B provided with laterally-adjustable bearing-blocks C, pivotal pin H, upper revolving portion D, means for adjusting the upper portion to receive game-boards of different sizes, 90 substantially as described.

2. In a revolving game-board holder, the laterally-extending arms B provided with depending bearing-blocks C, braces n, the revolving portion D having laterally-adjust- 100

able cleats X provided with shoulders or rabbits, substantially as described.

3. In a revolving game-board holder, the stationary portion B having depending laterally-adjustable bearing-blocks, longitudinal countersunk grooves e, pin d adapted to enter the said grooves and control the lateral movement of the block C, pivotal pin H, laterally-extending arms D, having on each end a rabbit and a shouldered cleat, the said cleat provided with longitudinal grooves g, and a set-

screw f screwed into the end of the arms D and adapted to control the lateral adjustment of the cleats X, substantially as described.

In testimony whereof I have signed my name to this specification in the presence of two subscribing witnesses.

HERMAN HENRY LIEBENBERG.
